UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

INCANDESCENT LAMP.

Application filed May 27, 1921. Serial No. 473,217.

This invention relates to illuminating devices having an incandescent lamp adjustably mounted within a reflector.

In devices of this kind, the adjustment is provided to enable the user to place the lamp directly in focus, or to shift its position relative to the focus so as to modify the character of the illumination obtained. Lamp bulbs, reflectors and holders are ordinarily so made that, when of standard size, the lamp filament is properly positioned at the focus of the reflector. But owing to unavoidable variation in manufacture, it frequently happens that one or more of the assembled members deviate from the standard in such manner that proper focus cannot be obtained, unless means are provided for relative adjustment. A further advantage of adjustability is that an illuminating device is made adaptable for varied service requirements when its light may be concentrated in a narrow, powerful beam or diffused to illuminate adequately a relatively large area.

The advantages to be obtained from focusing devices have been impaired in prior structures by reason of the extreme compactness of the lamp filament. In the endeavor to obtain an illuminant concentrated as much as possible at the focus of the reflector, usually having the form of a parabola of revolution, the incandescent filament has been formed into a spiral or otherwise contracted to a few one-hundredths of an inch in dimensions. If positioned exactly at the focus of the parabola, such filaments give a concentrated beam of light, but are not capable of adjustment to give a satisfactory diffused illumination. This is due to the fact that if the lamp is moved forward or backward from the focus to spread its light, no effective portion of the filament remains at the focus and substantially none of the emergent rays are parallel to the axis.

It is the purpose of my invention to provide an improved type of lamp capable of being focused, yet giving a satisfactory illumination through a range of adjusted positions. I achieve this purpose by the use of an elongated incandescent filament extending along the axis of the reflector. The invention will be described as applied to a tubular flashlight, as illustrative of one of the varied uses to which it may be put. The focusing means and associated shock absorbing device illustrated in the accompanying

drawings are claimed in my copending application Serial No. 466,639, filed May 4, 1921. The particular manner of focusing forms no part of the present invention and any suitable means for adjusting the lamp relative to the reflector may be used.

The invention will be further described in connection with the accompanying drawings, in which

Fig. 1 is a vertical section through a tubular flashlight embodying my invention, the battery being shown in elevation,

Fig. 2 is a vertical transverse section through the flashlight head, showing the novel filament,

Fig. 3 is a diagram illustrating the operation of the device, and

Figs. 4 and 5 are side elevations of lamp bulbs having alternative forms of incandescent filaments.

In the drawings reference numeral 1 indicates a casing of non-conductive material and 2 a battery of dry cells. A parabolic reflector 3 is retained against the end of casing 1 by a cover glass 4, which is rigidly held in metal head members 5 and 6. A switch 7 is operable to bridge a gap in contact strips 8 and 9, respectively in electrical connection with the zinc bottom of the lowest cell and the reflector 3. The latter is in conductive relation to the exterior terminal of the lamp, but is preferably retained out of contact with the head members 5 and 6, as shown, so as to prevent accidental short-circuiting through bridging of the exposed metal parts.

The focusing and associated shock absorbing means are illustrated in Fig. 2. Referring to that figure, an incandescent lamp 11 is screwed into a threaded holder 12, having an outwardly projecting annular flange 13 at its upper end. The reflector 3 is centrally apertured and is provided with a depending tubular portion 14 in which the holder 12 has a sliding fit. The tubular portion 14 is widened to form an annular seat 15 for the flange 13. The unthreaded lower portion 16 of the tubular lamp holder 12 extends below the base of the lamp and has an inturned bottom flange 17. A hollow cylindrical casing 18 surrounds the tubular holder 12 and has an annular bottom recess 19 shaped to receive the flange 17. Casing 18 is adapted to telescope upon the widened portion 20 of the reflector stem, but is normally held in the retracted position illustrated, by means of a

helical spring 21 which is under compression between the base of the casing and the seat 15 on the reflector. Flange 13 acts as a stop to limit downward movement of the holder 12.

- 5 Coincident perforations are formed in flange 17 and the base of recess 19. A tubular rivet 22 of conductive material extends through the perforations and is adapted to place the inner terminal of the lamp and the 10 carbon pole of the battery in electrical connection. Rivet 22 is spaced from the holder 12 and casing 18 by rigid discs 23 and 24, of insulating material, which abut respectively upon the flange 17 and the wall of recess 19. 15 The rivet ends are expanded or rolled outwardly in the usual manner to secure the discs and intermediate metal parts firmly together. When the discs are secured as described, the reflector, holder and casing are held in proper 20 adjustment and may be handled or inserted in the flashlight as a unit.

By adjusting the end cap 25, the rectilinear filament 26 may be moved forward or back along the axis of the reflector with respect to 25 the focal point 27. Upward motion of the cap 25 is transmitted to the battery and through the carbon electrode to the structure carrying the slideable lamp holder 12. The spring 21 is compressed on upward movement of the holder, and when the end cap is moved downwardly, permitting the spring to expand, it causes the holder to follow the descending battery, maintaining the electrical connection between the lamp and carbon 30 electrode. The threaded engagement of the end cap with the casing end holds the parts in any adjusted position.

With the foregoing construction, I can dispense with the spiral spring usually employed in the bottom cap to make contact with the zinc battery terminal. Instead of a spring, a contact making projection 28, having a plane surface in contact with the electrode, is provided on the bottom of the end 45 cap. The spring 21, adjacent the lamp, is of such strength that in any adjusted position of the spring or inclination of the flashlight it will have sufficient expansive force to hold the battery against the contact making projection 28. The spring may be made as strong as desired, up to the point where it would be too difficultly compressible to yield readily under impact of the battery.

The advantage of using an axially elongated filament instead of one compactly coiled will be apparent from the diagram, Fig. 3, which is drawn with a view to clearness of illustration and does not necessarily represent the actual proportions of the parts. 50 In this figure, three points on a rectilinear filament are taken for illustration. The point F coincides with the focus of the parabolic reflector, and the points F' and F'' lie on the axis respectively behind and in front 55 of the focus. For the sake of simplicity, rays

impinging upon the outermost reflective points P and P' only are considered. The lines PO and P'O are normals drawn to lines tangent to the parabola at P and P'. The rays FP, FP', emerging from the focus are 70 reflected parallel to the axis of the parabola. The rays F'P, F'P', however, projected from behind the focal point, have an increased angle of incidence and are therefore caused to diverge outward from the parallel through a 75 distance measured by the increased angle. Similarly, light traversing the paths F''P, F''P', approaches the normal at a less angle than the focal rays and is bent inward with respect to the parallel rays. 80

In a properly adjusted lamp, the condition just described obtains and the illumination is of a uniform character. It may be considered to be made up of a beam of parallel rays emerging from the light source at the focus, 85 and a surrounding envelope of rays produced by the parts of the source adjacent to the focus. In prior adjustable lamps, however, the incandescent filament has been made so short that if moved any appreciable distance 90 from the focus along the axis of the reflector, in order to spread the beam, substantially none of the light source remains at the focus. The result is the extinction of the greater portion of the rays which should be projected 95 parallel to the axis of the reflector and the illumination obtained is characterized by a bright ring surrounding a dull core.

According to my invention, the incandescent filament is of such length that it may be 100 adjusted to greatly extend the area of illumination without removing all of its effective portions from the focal area. In the diagram, the filament may be considered as extending between points F' and F'', and in 105 this position is bisected by the focal point F. When so adjusted, a concentrated beam of maximum intensity is obtained. If the area of illumination is to be increased, the filament is moved forwardly into the position FX. It 110 will be noted that a portion of the light source remains at F and parallel rays still emerge from the reflector. In this manner I am able to obtain a greatly enlarged uniformly lighted area. Similar results may be obtained by 115 adjustment of the filament toward the vertex of the reflector.

The essential feature of my invention is the combination with a reflector and focusing device of a lamp having a filament so shaped 120 as to insure adequate illumination in all adjusted positions. The filament need not be in the form of a straight wire to attain this result. It may for example, have the shape shown at 29, Fig. IV, or 30, Fig. V. The 125 invention may be applied also to reflectors of contours other than parabolic.

I claim:

A flashlight comprising the combination of a concave reflector having a central aperture; 130

a lamp having an elongated filament; an adjustable holder carrying said lamp and movable at will back and forth along the axis of said reflector and its aperture; a battery in circuit with said lamp; a tubular casing carrying said battery, holder, reflector, lamp and its filament in axial alinement; and means operative at will to adjust said holder, lamp and its filament along the reflector axis to alter the spread of the reflected light without

opening the circuit including said lamp and battery; said filament having a part thereof disposed at the focus of said reflector in every adjusted position of said lamp, whereby light from said filament may be projected at will as a concentrated beam of maximum intensity or as an enlarged diffused beam of uniform intensity. ¹⁵

In testimony whereof, I affix my signature.

LEE J. VOORHEES.
